UNITED STATES PATENT OFFICE.

IGNATIUS MAISANO, OF WILMINGTON, DELAWARE.

TOY.

1,358,768.

Specification of Letters Patent. Patented Nov. 16, 1920.

Application filed February 26, 1920. Serial No. 361,563.

To all whom it may concern:

Be it known that I, IGNATIUS MAISANO, a citizen of the United States, residing at Wilmington, in the county of New Castle 5 and State of Delaware, have invented new and useful Improvements in Toys, of which the following is a specification.

This invention relates to a toy for the amusement of children, and more particularly to a mechanical one representing a horse and rider which, when actuated, travels around a fixed circular undulating track, and in such travel rises and falls, such movement being attained by co-action between said fixed circular undulating track and certain feet of the horse, having means for engagement with said track, whereby said figure mounted on a pivot is caused to rock and appear to gallop as it travels in a circular path, and at the same time may ring a bell or chime, and effect a clicking sound in imitation of hoof beats. These amusing aims are accomplished in a simple and inexpensive manner by means herein- 20 after described and more especially set forth in the claims, reference being had to the accompanying drawings, in which—

Figure 1 is a side elevation of my improved toy. Fig. 2 is a top view thereof. 30 Fig. 3 is a sectional view on the line 3—3 of Fig. 2. Figs. 4 and 5 are sectional views of the undulating track, and Fig. 6 is a side view of a modification.

In the drawings, 10 is a base of circular 35 or other box-like form, preferably of sheet metal, with a similar cover 11, through the center of which is an opening 12 to form the bearing for a short shaft 13. The top of the cover 11 is provided near its outer edge 40 with a circular track 14 concentric with the opening 12 and having an undulating upper surface as shown. This surface is produced by a series of combined curved rises 15 and depressions 16. The undulating track 14 45 may be separate from and attached to the cover 11, or, as shown in Figs. 4 and 5, integral therewith.

Just above the cover 11 is a disk 17 of 50 diameter less than that of the inner edge of the track 14, which disk is secured to the shaft 13 so as to rotate therewith. On the lower end of the shaft 13, and within the base 10, is fixed a spur gear wheel 18 driven by a like wheel 19 fastened to a horizontal 55 shaft 20 which extends through the side of the base 10 and is bent to form a crank 21,

the turning of which rotates the shaft and the disk 17. Fastened on said disk near its edge is a rigid standard 22, the upper end of which is bent outwardly to form a horizontal pivot 23 on which is the figure 24 representing a horse and its rider. This pivot is near the center of the figure so that the latter may rock vertically. If desired two or more horsemen may be mounted 60 on the disk 17. The horse is arranged so that its front and hind feet reach over the track, they being placed a short distance above said track so as to permit the rocking of the horse, this being accomplished 65 by pivoting a roller 25 to a front foot, as in Fig. 1, or to a hind foot, as in Fig. 6, which engages the undulating surface of the track 14. The contact is preserved by a contractile spring 26 fastened to the other fore or 70 hind foot and to the disk 17, or to a projection 75 27 at the edge thereof.

Upon turning the crank 21 the disk 17 is rotated by means of the gear wheels 18 and 19, and said disk through the instrumentality of the standard 22 in turn causes the horseman to travel around the track 14, and the roller 25 running over the undulating surface of said track rocks the horseman on its pivot 23. 80

The roller 25 may be and preferably is a bell having contained therein balls as shown in Figs. 1 and 6, which rings as it moves over the track and so adds to the attractiveness of the toy. 85

In connection with the figure, 24 is a device for producing a clicking sound in time with the movement of the horse and suggesting hoof beats. This device consists of a box 28 from which projects a thin spring 90 metal tongue 29 having a buckled depression 30. The free end of this tongue extends under one of the feet of the horse and is depressed by the downward movement of said foot. When the foot rises the spring 100 tongue returns to its normal position. 95

The toy may be made of sheet metal and, being of simple construction, the cost of manufacture is reduced to the minimum.

I claim:—

1. A mechanical toy comprising a box-like base, a circular track, having an undulating upper surface, secured on the top of the base near its outer edge, a disk within said track parallel to the base top and pivoted in the center thereof, means for rotating said disk, a figure of a horse and rider 110

5 pivotally supported by said disk above said track and having a member reaching over said track, and a roller carried by the figure in forced contact with the undulating face of the track to cause said figure to rock as it rotates with the disk.

10 2. A mechanical toy comprising a box-like base, a circular track, having an undulating upper face, secured on the top of the base near its outer edge, a disk within said track parallel to the base top and pivoted in the center thereof, gearing for rotating said disk, a vertical standard secured near the edge of the disk, a figure of a horse and rider 15 pivotally supported on said standard above said track and having a member reaching over said track, a roller journaled on said figure in contact with said undulating face, and a contractile spring for maintaining 20 contact of the roller with said undulating face.

20 3. A mechanical toy comprising a box-like base, a circular track having an upper face integrally formed with the top of the

base near its outer edge, a rotatable disk 25 parallel to the base top, a shaft fixed to said disk, a gear wheel on said shaft within the base, a horizontal shaft extending into the base having a crank on its outer end and a gear wheel on its inner end engaging the 30 first named gear, a standard extending vertically from near the edge of said disk, a figure pivotally supported on said standard above the track, a rolling bell pivoted to said figure in contact with the undulating 35 face of the track, a contractile spring connected to said figure and to the disk to hold the bell upon said undulating face, a rattle or clicker attached to said base, and means for giving a clicking sound in the movement 40 of the horse.

In testimony whereof I affix my signature in presence of two witnesses.

IGNATIUS MAISANO.
